UNITED STATES PATENT OFFICE.

ISSIDORE MRAGODANOVITCH, OF NEW YORK, N. Y.

BOOK COVER.

Application filed September 4, 1924. Serial No. 735,838.

To all whom it may concern:

Be it known that I, ISSIDORE MRAGODANOVITCH, a citizen of the United States, and resident of the city of New York, in the county of New York and State of New York, have invented certain new and useful Improvements in Book Covers, of which the following is a specification.

The present invention relates to book covers, or in other words to protecting means placed outside the bodies of books and overlying the same.

When books are subjected to hard usage, the connection between the backs and the sides of the covers thereof are usually first to suffer. This is due to the fact that the connection or hinges, as they are sometimes called, are, in using the book, frequently bent back and forth, that is to say in opposite directions, and the connection is thus apt to be severed in time.

The main object of the invention is to provide a book cover, wherein the connection between the back and the sides thereof is made of rubber or like material, thereby withstanding hard usage.

A further object of the invention is to provide a book cover, all of the elements of which are made of rubber and united by vulcanizing action.

A further object of the invention is to provide the sides of a book cover with inwardly projecting flanges, preferably, adjacent the free corners thereof, thereby providing means for protecting the corners of the book.

A still further object of the invention is to produce corner protectors of the type mentioned which are made integral with the sides of the cover.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of

the invention is illustrated in the accompanying drawings, in which:

Figure 1 is a side elevation of a book cover constructed in accordance with the present invention; Fig. 2 is an inner view 60 of the book cover in its open position; and Fig. 3 is a section taken on line 3-3 of Fig. 2.

In the drawings, the numerals 10 and 11 indicate the front side and the rear side, respectively, of a book cover, each being of oblong configuration and comprising a sheet of rubber of a suitable thickness. The sheet may be either soft or hard, according to the requirements, and is provided along its inner longitudinal edge with a kerf 12 in its inner face. Into this kerf is fitted one of the longitudinal edges of a, preferably, soft rubber sheet 13, which constitutes the back of the cover. The elements are united by vulcanizing action in any suitable manner. To the inner face of the back may be secured in any suitable manner, for instance by cement, a rigid oblong plate member 14, to stiffen the back, if 80 desired.

Each of the sides of the cover is provided along its free edges with an inwardly projecting flange 15, provided with notches 16 at suitable intervals, each of said notches 85 being of a size to accommodate a finger of the user. These flanges serve to protect the corners and edges of the leaves of the book. The height of each flange depends obviously upon the thickness of the book it being, however, obvious that these flanges need not contact with one another when the book is in its closed position. The flanges may be provided only adjacent the corners of the book, if desired, or they may be of a 95 greater length according to the requirements. In the case illustrated, the flanges extend each throughout the length of a side of the book, but do not extend throughout the widths thereof, as clearly shown in 100 Figs. 1 and 3 of the drawings.

It is obvious that, while herein the sides of the book have been described as being made of rubber, they may be made of any other suitable material. It is, however, essential that the connections between the back and sides be made of rubber, to allow of repeated opening and closing of the book without injuring the said connection.

As appears from Fig. 1 of the drawings, 110

- the sides 10 and 11 of the cover overlie the leaves 17 of the book, the said leaves, however, fitting between the flanges on the said sides, whereby they are properly protected.
- 5 Inasmuch as the flanges 15 are made integral with the sides of the book cover, they afford always proper protection to the leaves of the book. The notches 16 serve to facilitate opening of the book, the user inserting two of the fingers into two notches of opposite sides of the cover, thereby gripping the leaves of the book for opening the same.
- What I claim is:—
- 15 1. A book cover comprising a front side, a rear side, each of said sides being provided with a kerf in its inner face along its inner longitudinal edge, and a back made of rubber having its longitudinal edges fitted into said kerfs.
- 20 2. A book cover comprising a front side, a rear side, each of said sides being made of rubber and provided with a kerf in its inner face along its inner longitudinal edge, and a back made of rubber having its longitudinal edges fitted into said kerfs and attached to said sides by vulcanizing action.
- 25 3. A book cover comprising a front side, a rear side, each of said sides being pro-
- vided with a kerf in its inner face along its inner longitudinal edge, and a back made of soft rubber having its longitudinal edges fitted into said kerfs.
4. A book cover comprising a front side, a rear side, each of said sides being made of rubber and provided with a kerf in its inner face along its inner longitudinal edge, and a back made of soft rubber having its longitudinal edges fitted into said kerfs and attached to said sides by vulcanizing action.
5. A book cover including a side having an inwardly projecting flange around each of its free corners, said flange being immovable in relation to said side.
- 45 6. A book cover including a side having an inwardly projecting flange made integral therewith around each of its free corners, said flange being immovable in relation to said side.
7. A book cover according to claim 5, said flanges being provided with notches.
8. A book cover according to claim 6, said flanges being provided with notches.

Signed at New York, in the county of 55
New York and State of New York, this 3rd
day of September, A. D. 1924.

ISSIDORE MRAGODANOVITCH.
